United States Patent

Des. 239,293

Patented Mar. 23, 1976

239,293

COMPUTER OR SIMILAR ARTICLE

John Warren Carroll, III, Pepperell, Mass., assignor to
Data General Corporation, Southboro, Mass.

Filed Nov. 7, 1974, Ser. No. 521,814

Term of patent 14 years

Int. Cl. D14—02

U.S. Cl. D26—5 C

FIG. 1

FIG. 2

FIG. 3

FIG. 4

FIG. 1 is a front perspective view of a computer showing my new design.

FIG. 2 is a rear perspective view thereof.

FIG. 3 is a top plan view thereof.

FIG. 4 is a right side elevational view thereof.

The side of the article which is not shown is a substantial mirror image of the right side disclosed in FIG. 4 except there are no vent slots.

I claim:

The ornamental design for a computer or similar article, as shown and described.
